UNITED STATES PATENT OFFICE.

JACOB B. CAMPBELL, OF YONKERS, NEW YORK, ASSIGNOR TO WILLIAM JAMES HOGG, OF WORCESTER, MASSACHUSETTS.

DESIGN FOR CARPET.

SPECIFICATION forming part of Design No. 25,540, dated May 19, 1896.

Application filed April 23, 1896. Serial No. 585,135. Term of patent 31 years.

To all whom it may concern:

Be it known that I, JACOB B. CAMPBELL, a citizen of the United States, residing at Yonkers, in the county of Westchester and State 5 of New York, have invented and produced a new and original Design for Carpets.

My invention relates to a design to be worked into or upon carpeting or similar fabrics; and I do hereby declare that the drawing accompanying this specification gives and conveys to any one skilled in the art of carpet-weaving a clear understanding of the same that is sufficient to enable such persons to use my invention.

15 The said drawing is a face view of a carpet embodying my new design. The drawing illustrates a body and a border.

The body A consists of a substantially uniform groundwork, upon which appear 20 connected sprigs of leaves arranged so as to form a wreath shape and inclosing a small floral figure having pointed petals. These wreaths are all alike and are arranged diagonally as to each other. Between the wreaths 25 appears a small diaper-work formed by short curved lines.

The border B consists of a substantially uniform groundwork, upon which appear fes-

toons or hanging wreaths of small leaves and flowers of a daisy shape. Below these appear 30 sprigs of leaves conforming to those in the body, but having a general vertical direction. Above the festoons appear sprigs of flowers and leaves similar to those forming the festoons. The outer edge is characterized by 35 the same diaper-work as appears in the body, and the inner edge is defined by a little of the same work. The extreme outer edge is left perfectly plain.

The colors employed for the different portions of this design may be varied to suit the convenience or taste of the manufacturer.

What I claim, and desire to secure by Letters Patent, is—

1. In a design for carpeting, the body A, 45 substantially as shown.
2. In a design for carpeting, the border B, substantially as shown.
3. The design for carpets, consisting of the body A and the border B, substantially as 50 shown.

JACOB B. CAMPBELL.
